(57) **CLAIM**

The ornamental design for a handle, as shown and described.

DESCRIPTION

FIG. 1 is a top, front perspective view of a handle showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof; and,

FIG. 8 is another perspective view thereof, the broken line showing of the unclaimed loudspeaker being shown as environment.

The broken lines in the figures illustrate portions of the design that form no part of the claimed design.

The shading is provided merely to represent contours of the design and does not connote the character of the surfaces such as any specific texture, material, gloss, translucence, transparency, surface treatment, or surface decoration.

The inventive aspects of the current embodiments exist in the handle as a whole, in individual portions and/or elements thereof, and in combinations of portions and elements thereof. Applicant reserves the right to amend this application and/or to file one or more continuing applications to specifically claim any such arrangement or any specific embodiment or embodiments, including changing solid lines to broken lines to denote unclaimed subject matter by amendment or in a continuing application.

The present embodiments may therefore include alternative embodiments that include fewer or more features. For example, referring to FIGS. 1-8, some or all of the front portions and/or side portions, which are shown in solid lines, may be excluded from a claimed design and shown in broken lines and unshaded areas. As another example, also referring to FIGS. 1-8, some or all of the front portions, the side portions, the top portions, the bottom portions, and/or the rear portions, which are shown in broken lines, and portions thereof, may be included in a claimed design and shown in solid lines. In addition, the present embodiments may also include alternative embodiments comprising corresponding line schematics of the schematics and images of

(Continued)

Appendix FIGS. A1-A61, in which some or all of the features of the schematics and images are depicted in solid lines and/or broken lines. For example, some or all of the housing, the grille portions, the front portions, the side portions, the top portions, the bottom portions, the rear portions, the speaker portions behind the grille, the seams, the badge portions, the handle portions, the connector portions, the feet portions, the fastener portions, the knobs, the buttons, the ports, the vent openings, the indicators, the text, and/or the indicia, as whole parts or as portions thereof, may be excluded from a claimed design and shown in broken lines. In addition, it should be noted that any wire frame lines on the handles shown in Appendix FIGS. A1-A61 represent edges and/or contours and not surface ornamentation.
